(57) **CLAIM**

The ornamental design for a front bumper for automobile, as shown and described.

DESCRIPTION

FIG. 1 is a front perspective view for a “front bumper for automobile” showing my new design,
FIG. 2 is a rear perspective view thereof,
FIG. 3 is a front view thereof,
FIG. 4 is a rear view thereof,
FIG. 5 is a left-side view thereof,
FIG. 6 is a right-side view thereof,
FIG. 7 is a top view thereof; and,
FIG. 8 is a bottom view thereof.

The design includes a contrast in color. However, no particular colors are claimed. Both the light and darken portions of the front bumper for automobile and the contrasting relationship between colors therein form a part of the claimed design.
